DESIGN FOR A COMBINATION LAMP AND FISH BOWL

Herbert F. Crewse, Des Moines, Iowa

Application January 31, 1938, Serial No. 74,760

Term of patent 3½ years

To all whom it may concern:

Be it known that I, Herbert F. Crewse, a citizen of the United States and resident of Des Moines, Polk County, Iowa, have invented a new, original, and ornamental Design for a Combination Lamp and Fish Bowl, of which the following is a specification, reference being had to the accompanying drawing, forming a part thereof.

Fig. 1 is a side elevational view of a combination lamp and fish bowl, showing my new design; and

Fig. 2 is a top plan view thereof.

I claim:

The ornamental design for a combination lamp and fish bowl, substantially as shown.

HERBERT F. CREWSE.
